PIANO ACTION

Francis C. Socin, Batavia, Ill., assignor to The
Rudolph Wurlitzer Company, Chicago, Ill., a
corporation

Application March 23, 1945, Serial No. 584,353

5 Claims. (Cl. 84—240)

1

This invention relates to a new and improved direct blow piano action, particularly adapted for use in low upright spinet type pianos.

It is the object of the invention to provide a direct blow action of compact construction such as will enable its use in a low spinet type piano where it is desired that the striking point of the hammer be at a minimum distance above the key bed.

One feature of the invention resides in the construction and relation of the wippen with respect to the striking action of the key coupled with a laterally extended flexible jack. Thus, it comprises a direct blow type action, all as will be more fully set forth and described in the following specifications.

Another feature of the invention resides in the provision of a double acting spring in association with the hammer butt to assist and accelerate the hammer let-off and return to rest position; and to equalize the movements of the action to provide for positive and smooth acting repetitive qualities in cooperation with the associated spring or springs as hereinafter described.

The full nature of the invention will be understood from the accompanying drawings and the following description and claims:

Fig. 1 is a side elevation showing a unit of the action in its rest position.

Fig. 2 is the same as Fig. 1 showing the action in striking position.

Fig. 3 is the same as Fig. 1 showing a modified form of unit.

Fig. 4 is a partial view showing a further modification of the unit.

In the drawings there is shown a key bed 10 upon which a piano key 11 is pivotally supported in the usual and well known manner. The key is provided at its operating end with a striking head 12 rounded to slidably engage the cushion bed pad 13 carried by a finger 14 through which the striking action is transmitted to a vertically extending wippen 15.

The wippen 15 is pivotally supported adjacent its lower end at 15a upon a lower flange rail 16 of a supporting frame by the flange 17 and at its opposite upper end is pivotally connected at 18 to the finger 14. Said finger has an extension 19 through which a screw threaded button 20 extends for adjustment to and from the striking head of the key. The pad 13 supported on the lower end of the finger 14 adjacent the end of the key 11 extends over and between the striking head and the button. Thus, the striking head imparts a direct blow through the adjustable but-

2

ton 20 and finger 14 to the wippen such as to cause a forward striking action of the wippen.

The hammer 21 is mounted in alignment with the piano string 22 being carried by the arm 5 23 extending from the end of one arm of an L-shaped hammer butt 24. The other arm of the hammer butt 24 is pivotally mounted by the flange 25 upon the flange rail 16. In rest position the hammer lever rests upon the cushioned back rail 26. The striking movement of the wippen is transmitted to the hammer through the hammer butt by a flexible jack. Said flexible jack comprises the jack member 27 pivoted at 28a to the wippen intermediate its ends. This member of 10 the jack is pivoted to a link member 28, which in turn is pivoted at 28b to the hammer butt intermediate its arms. The general relative arrangement and position of the jack is at an angle extending downwardly and laterally from the wippen to the hammer butt.

Said jack is provided with a heel portion 29 adjacent its pivotal mounting 28a for engagement with the regulating button 30 adjustably carried upon the rail 31. That arm of the L-shaped hammer butt, which is pivoted to the flange rail, is provided with a let-off bumper 32 engageable with the pivotal connection between the link member 28 and jack member 27.

The flange 17 for pivotally supporting the wippen carries a spring arm 33 bearing against the forward face of the wippen near its pivotal connection with the jack, said spring arm 33 tending to return the wippen to rest position. Also, carried by the wippen there is a spring arm 34 extending along the under side of the jack member 27 with its free end connected thereto, which tends to return the flexible jack to its rest position. Also, mounted upon the upper end of the wippen there is a back check 35 engageable by 35 the hammer in its let-off position shown by dotted lines in Fig. 2.

The damper 36 is carried by a damper arm 37 rigidly mounted to extend directly upwardly from the damper lever 38. Said lever 38 is fulcrumed 45 intermediate its ends upon the support flange 39 mounted upon the flange rail 16. Said lever is actuated by the actuating finger 40 mounted on the lower end of the wippen below its supporting flange 17. Thus when the wippen is struck forwardly, the finger 40 swings downwardly against the lever 38, which in turn swings the damper arm 37 rearwardly, carrying the damper free of the string, said damper being returned to damping position through the spring 41. Said spring 50 41 is secured to the flange 39 and has its free end

extending over and bearing upon the end of the damper lever carrying the damper arm 31.

The action is such that upon actuation of the key its striking head imparts an upward movement to the finger 14, which, being pivoted to the upper end of the wippen, drives it forwardly. Since the flexible jack is normally in overcenter position its forward and downward movement imparts a corresponding movement to the hammer butt, swinging it forwardly and downwardly to throw the hammer into striking engagement with the string. However, this movement causes the heel 29 to engage the regulating button 30 and throws the let-off bumper 32 against the pivoted connection between the jack members, whereby the jack is flexed to permit the let-off of the hammer to the dotted line position, Fig. 2. Upon the key returning to rest position, the spring 33 will cause the wippen to follow it and the spring 34 will return the jack to its rest position. Said springs 33 and 34, coupled with the flexing of the jack, gives the action the desired double repetition.

The double repetition action is furthered by providing a spring 50 having a separate end anchored to the spring rail 51 and its lower end bearing against the upwardly extending arm of the hammer butt 24. The spring rail 51 is positioned to act as a buffer or stop for the damper 36, the spring depending therefrom and bearing against the hammer butt tending to oppose the striking action of the hammer. Under the tension of said spring the let-off action of the hammer following the blow is facilitated, the spring assisting the natural recoil thereof. Also, when the hammer is in check against the back check 35, said spring partially equalizes the tension of the spring 34 in returning the flexible jack to rest position. The equalization of said spring eliminates any violent kickback of the flexible jack as the hammer and jack are returned to rest position. Thus, as the performer's fingers release their pressure on the keys, the hammer is thrust gently toward the string but not enough to touch it, at the same time the flexible jack being gently but positively returned to normal or rest position, whereby the performance of the action becomes typical of that of a grand piano action generally referred to as a double repetition.

Fig. 3 shows a modified form of the above described action wherein a double acting spring 150 is removably anchored and supported at one end by the pin 152 provided in a downwardly extending heel 153 formed on the hammer butt 24. Its upper end is anchored to the spring rail 51. The spring is formed L-shaped about a coil 154 formed therein intermediate its ends.

That portion of the spring between the rail 51 and its coil 154 acts as a floating spring arm permitting lateral movement of the coil. The portion thereof extending from said coil to the pin 152 exerts an upward pressure on the hammer butt 24 about its pivotal support on the rail 16. This action assists the let-off and return of the hammer to rest position. This results in a much smoother, frictionless action to the escapement.

Fig. 3 further illustrates the provision of an elongated finger 114, which is in the nature of an adapter for accommodating the action to a larger size piano or case. Thus in Fig. 3 the action is shown raised somewhat with respect to the key bed 10 and piano key 11. With this arrangement the elongated finger or adapter 114 is pivoted to the wippen 15 at 118 adjacent its upper end and is provided with the extension 119 through which

the screw threaded button 120 extends for adjustment to and from the elevated striking head 112 mounted upon the key. The end of the adapter finger 114 carries a cushion pad 113 and the button 120 carries a similar but separate cushion pad 113-A. However, said pads may be joined as in one piece as illustrated by the pad 13 of Fig. 1.

In the modified form shown in Fig. 4, the wippen 215 is actuated by a bell crank in place of the finger 14, the bell crank having an upstanding finger 214 associated with the upper end of the wippen and positioned to strike it forwardly through the medium of the pad 213. The angularly and laterally extending portion of the bell crank lever indicated at 220 is directly engaged through a pad 213 by a capstan screw 212 carried by the striking end of the piano key 211. The bell crank lever is pivotally supported intermediate its ends on the upper flange rail 219 of the supporting frame through pivotal flange support 219-A. Thus, the key is actuated and strikes upwardly against the arm 220 of the bell crank lever, throwing the upstanding finger 214 thereof laterally against the upper end of the wippen 215 for transmitting such lateral swinging movement of the wippen to the hammer through the flexible jack 21.

The invention claimed is:

1. A piano action including a piano key, a hammer positioned to strike the piano string, a supporting frame, a wippen pivotally mounted at one end upon said frame below said key to extend substantially vertically with respect to and terminating above said key, a striking member associated with the upper end of said wippen engageable by the striking end of said key to swing said wippen forwardly toward the string, a hammer butt pivotally supported by said frame carrying said hammer on one end thereof, a jack pivotally connected with said wippen intermediate its ends and extending downwardly and forwardly toward the string into operative engagement with said hammer butt for transmitting the striking action of said key therethrough to said hammer, and a spring anchored to said frame extending upwardly into engagement with said wippen intermediate its ends tending to return it to rest position after being actuated.

2. A piano action including a piano key, a hammer positioned to strike the piano string, a supporting frame including a lower flange rail and an upper flange rail, a wippen pivotally mounted on said lower flange rail below said key to extend upwardly thereabove, a jack pivotally mounted on said wippen intermediate its ends for operative engagement with said hammer to transmit movement therebetween, and an actuating finger pivotally mounted on said upper flange rail intermediate its ends having an upstanding portion associated with the upper end of said wippen and a laterally extending portion overlying the striking end of said key through which upward movement of said key will transmit lateral movement to the upper end of said wippen.

3. A piano action including a piano key, a hammer positioned to strike the piano string, a supporting frame including a spring rail, a wippen pivotally mounted upon said frame, a striking finger associated with said wippen engageable by the striking end of said key to swing said wippen about its pivotal mounting, a hammer butt pivotally supported by said frame carrying a hammer on one end thereof, a jack engaged with said wippen intermediate its ends and extending into operative engagement with said hammer butt for

transmitting the striking action of said key therethrough to said hammer, and a double acting spring interposed between the spring rail of said supporting frame and said hammer butt tending to return said hammer from said string to implement its let-off action, said spring being formed with a coil intermediate its ends to provide a floating spring arm.

4. A piano action including a piano key, a hammer positioned to strike the piano string, a supporting frame including a spring rail, a wippen pivotally mounted upon said frame, a striking finger associated with said wippen engageable by the striking end of said key to swing said wippen about its pivotal mounting, a hammer butt pivotally supported by said frame carrying a hammer on one end thereof, a jack engaged with said wippen intermediate its ends and extending into operative engagement with said hammer butt for transmitting the striking action of said key therethrough to said hammer, and a double acting L-shaped spring formed with an intermediate yielding formation intermediate its ends to provide an upwardly extending floating arm with its upper end connected to said spring rail, and a laterally extending arm connected to said hammer butt, to thereby assist the let-off and return of the hammer to rest position.

5. A piano action including a piano key, a hammer positioned to strike the piano string, a supporting frame including a spring rail, a wippen pivotally mounted upon said frame, a striking finger associated with said wippen engageable by the striking end of said key to swing said wippen about its pivotal mounting, a hammer butt

35

pivotedly supported by said frame carrying a hammer on one end thereof, a jack engaged with said wippen intermediate its ends and extending into operative engagement with said hammer butt for

5 transmitting the striking action of said key therethrough to said hammer, a spring having one end anchored on said wippen and its opposite end connected with said jack tending to return said jack to normal rest position after actuation, and 10 a double acting spring interposed between the spring rail of said supporting frame and said hammer butt tending to return said hammer from said string to implement its let-off action, said last mentioned spring being formed with a yielding 15 formation intermediate said frame and butt to provide a floating action therebetween.
